UNITED STATES PATENT OFFICE.

ROBERT W. ELLINGHAM, OF SPRINGFIELD, MASSACHUSETTS.

GOLF CLUB.

Application filed December 14, 1922. Serial No. 606,914.

To all whom it may concern:

Be it known that I, ROBERT W. ELLINGHAM, citizen of the United States, residing at Springfield, in the county of Hampden and State of Massachusetts, have invented new and useful Improvements in Golf Clubs, of which the following is a specification.

The present invention relates to golf clubs and more particularly to golf clubs commonly known as "putters".

One object of the invention is to provide a golf club having improved means whereby the weight of the head of the club may be varied and the distribution of said weight adjusted to suit the requirements of the user.

Another object of the invention is to provide certain new and useful improvements in golf club construction for the purpose of reinforcing the striking face and otherwise strengthening the head of the club without detracting in any way from the desired neat and attractive appearance thereof.

Another object of the invention is to provide, in a putter having a head constructed largely of wood and faced with metal at the putting side thereof, means adapted to perform the dual function of reinforcing said metallic facing and affording a permanent and distinct visual indication of the correct line of putt.

To the accomplishment of these objects the invention consists in the features of construction and in the combinations and arrangements of parts hereinafter described and claimed.

In the accompanying drawings,

Fig. 1 is a top plan view of the head of a putter constructed in accordance with the present invention;

Fig. 2 is a rear elevational view of the putter head;

Fig. 3 is a sectional view taken along the line 3—3 of Fig. 1; and

Fig. 4 is a sectional view taken along the line 4—4 of Fig. 2.

Referring to the drawings, the head of a golf club commonly known as a "putter" is indicated at 5. The putter head is constructed partially of metal and partially of wood, the metallic portion of the head being in the nature of a frame as indicated at 6 while the wooden portion of the head consists of two solid blocks 7 which are

shaped to fit snugly in cavities provided to receive them in the frame 6. The frame 6 consists of an integral casting of aluminum or other material having the required specific gravity and tensile strength. The frame is formed with a neck 9 having a socket therein to receive the shaft of the club, an upright wing portion 10 the outer side of which constitutes the putting face, and a sole or ground portion 11 which extends at right angles to the putting face and protects the bottom of the blocks 7 from wear.

Formed at the upper side of the sole 11 of the frame and connecting the sole 11 with the upright wing portion 10 is a cylindrical protuberance 12 which extends at right angles to said wing portion and is located substantially midway between the toe and heel of the sole 11. The protuberance 12 is axially bored from the rear of the frame to provide a recess or pocket 13 for the reception of a removable weight or balance-changing unit 14 comprising one or more separable members for use in adjusting the balance of the club or changing the weight thereof as will be hereinafter explained. The protuberance 12 also serves to stiffen and reinforce the upright wing portion 10 in its central portion where it strikes the ball and helps to maintain the striking face of the club at the requisite angle relatively to the bottom face thereof. By reason of this reinforcement the head is adapted to be used for driving as well as for putting. The sole 11 of the frame is also provided with threaded apertures in the toe and heel portions thereof, as at 15 and 16, and the wooden blocks 7 are bored from their lower sides, the bores in said blocks being located to register with the apertures 15 and 16 and being adapted to receive weight units 17 and 18, respectively, which are similar to and may be used in conjunction with the weight units 14 for adjusting the balance of the club.

The wooden blocks 7 are fashioned to impart the required contour to the club head and they are rigidly secured in place by means of screws 20 which extend through the sole portion 11 of the frame. The blocks 7 are of substantially uniform thickness throughout from their top to their bottom faces. The cylindrical surfaces of the hollow protuberances 12 do not rise to the level of the upper faces of the blocks but a ridge

or fin 22 extends axially along the highest portion of the protuberance between the two blocks 7, the upper face of said fin being flush with the upper faces of said blocks as well as with the upper edge of the upright wing portion 10. The fin 22 extends from the middle of the upright wing portion 11 and at right angles to the striking face thereof, and constitutes a permanent and distinctive line or marker for indicating the line of putt. Preferably the blocks 7 are of a dark reddish color when finished so that the aluminum fin 22 will stand out clearly by contrast with the dark wood at each side thereof and will thus afford a guide line which can be easily and distinctly seen by the player when addressing the ball.

The weight unit 14 comprises one or more disks or collars 24 which are threaded upon 20 the reduced shank portion of a screw 25. The screw 25 is provided with a portion of enlarged diameter adjacent its head 26, the enlarged portion 25 being screw-threaded into the socket 13. The head 26 is provided 25 with a segmental slot 27 which is adapted to receive the edge of a coin by means of which the screw may be turned for the purpose of removing or inserting the same and thus removing or replacing all the weight collars 30 by a single operation. The weights or collars 24 are preferably made of Babbitt metal which is heavy and sufficiently hard to properly retain the shape of the screw threads. Three collars or weights 24 are shown upon 35 the screw 25 but more or less may be used as may be found desirable.

The weight units 17 and 18 at the heel and toe of the club are similar to the weight unit 14 already described, and are carried in a 40 similar manner by means of screws 28 which have enlarged shank portions 29 that are threaded into the apertures 15 and 16 in the sole 11, and reduced shank portions 30 upon which are threaded one or more weights or 45 collars 31 which, together with the screws 28, constitute the weight units 17 and 18. The screws 28 are provided with heads 32 having coin slots therein to facilitate their insertion and removal, the heads being flat and arranged to be flush with the bottom face of 50 the sole 11 when the screw is tightened in place. The masses of weight represented by the collars 31 may be varied at will by varying the number of separate collars upon the screws 28. The collars 31 are interchangeable upon the two screws 28. The above 55 described construction and arrangement of the weight units is such that the user of the club may adjust or rearrange the weights at will to shift the center of gravity of the club to obtain the desired balance or to offset the user's tendency to vary from the true line of putt. For example, if a player finds that the ball invariably goes to the right of the hole 60 this condition may be rectified by lightening

the weight of the toe and increasing the weight of the heel through rearrangement of the weights in the toe and heel recesses. On the other hand if he finds he has a tendency to putt the ball to the left of the hole he will be able to putt nearer to the true line if he rearranges the weights in the toe or heel recesses or both to make the toe heavier than the heel. The weights in the central recess may be rearranged as desired to vary the 75 weight of the club head or to transversely adjust its center of gravity.

With the above described construction, the 80 adjustments of the weights may be made as all the weights in each recess are assembled together upon a single holder in the form of a screw, the weights and the screw itself, in each instance constituting a single weight element which may be removed as a 85 unit by loosening and withdrawing the screw, or which may be inserted as a unit and locked securely in place by tightening the screw. Inasmuch as the screws are provided with coin slots the screws may be conveniently 90 removed and replaced with the aid of any ordinary coin. Obviously, the screws may be used without the weights if it is desired to lighten the club to that extent. It is further pointed out that by reason of the 95 fact that the longitudinal axes of the weight units 17 and 18 are disposed in the longitudinal medial plane of the head, the toe and heel balance of the head may be varied as 100 may be desired without shifting the center of gravity transversely of the head.

The invention has been disclosed herein for 105 illustrative purposes in an embodiment at present preferred but it is to be understood that the scope of the invention is defined by the appended claims rather than by the foregoing description.

What is claimed and desired to be secured by Letters Patent is:—

1. A putter head having a weight-receiving recess extending forwardly from its rear face substantially midway of the heel and toe, and similar recesses extending upwardly from the bottom face of the head at the heel and toe, a screw for each of said recesses 110 each screw having a relatively short shank adapted to be threaded into the mouth of the recess and a threaded shank extension of reduced diameter, and a plurality of weights adapted to fit loosely in said recess 115 and having threaded apertures for receiving said shank extensions whereby said weights may be assembled side-by-side upon said screws so as to be removable with the 120 screws.

2. In a golf club, the combination of a 125 head having a weight-receiving recess therein, and a weight element adapted to be received in said recess, screw-threaded at its mouth and a weight element adapted to be 130

received in said recess, said element comprising a screw having a threaded shank of smaller diameter than said recess and a threaded enlargement of said shank adjacent the head of the screw for interengagement with the threaded mouth of said recess whereby said element may be rigidly but removably secured to said head, a plurality of separable weight collars threaded upon said screw shank and capable of adjustment thereon for varying the weight or balance of the head.

5 10 15

3. A putter head comprising non-metallic toe and heel blocks and an integral metallic frame partially enclosing and rigidly se-

cured to said blocks, said frame consisting of a sole plate for protecting the bottom of the head, an upright wing portion providing a striking face, a neck having a socket to receive the shaft, and a strengthening web connecting said heel plate and wing portion, said web extending between the toe and heel blocks at right angles to said wing portion and having its upper edge flush with the upper faces of said blocks to serve as a guide for indicating the line of putt.
